RING AND TRAVELER FOR SPINNING MACHINES

Application filed November 15, 1930. Serial No. 495,970.

This invention relates to the textile art and has special reference to improvements in the spinning rings and travelers employed in the spinning of silk and the like.

In the usual construction of devices of this character there is provided a ring which is so mounted in a holder that the ends of a traveler of thin spring wire may engage beneath the inner part of the ring and move freely around the bobbin which lies centrally of such ring. Because of the stress on the traveler due to the upward pull of the strand and because of the high velocity at which the traveler moves around the ring a very great friction is developed between the ends of the traveler and the ring. The traveler must be very light yet strong so that it is made of high carbon spring steel wire and it is thus very hard. Consequently if steps are not taken to prevent such action, a great deal of wear takes place on the ring and such wear speedily tends to impair the action of the traveler so that the latter no longer moves smoothly around the ring but has a more or less irregular or jerky motion. This interferes seriously with the spinning operation and frequently produces breakages of the silk and inequalities of tension therein even when not broken.

Efforts have been made to overcome this wear by so constructing the ring as to form a lubricant reservoir feeding to the contact surface between the flyer and ring. Such constructions are necessarily somewhat complicated and are also expensive to manufacture. Other efforts have been made to decrease the wear by bending the tips of the traveler downwardly so that the under side of the ring is contacted by the outside or convex portion of the bend. Such an arrangement is only partially successful since the bend wears a groove into the ring only less rapidly than the end of the wire where the bend is omitted and the end contacts with the ring. Still other efforts have been made by providing a flat surface on the under side of the ring and bending the traveler to provide a straight portion contacting throughout with this flat surface. This, however, results in increasing the frictional resistance

against movement of the traveler even though the wear is decreased and such increase of resistance is highly objectionable.

Furthermore, rings of this description are usually turned on a lathe from steel and are correspondingly expensive.

Because of the facts mentioned above it is one of the objects of the present invention to provide an improved form of ring and traveler wherein friction and wear will be reduced to negligible quantities with the use of very little lubricant and without the use of special devices for feeding lubricants.

A second object of the invention is to provide an improved arrangement of ring and traveler wherein any wear of the ring which does occur will be of such nature as not to interfere with the smooth running of the traveler.

A third object of the invention is to so shape the ring and traveler that, under all running conditions the contact between the two will be a one point contact between two tangentially arranged portions of the ring and traveler respectively.

A fourth important object of the invention is to provide an improved construction of ring wherein the ring is formed from a unitary stamping of sheet metal.

With the above and other objects in view, as will be presently understood, the invention consists in general of certain novel features of construction and combinations of parts hereinafter fully described, illustrated in the accompanying drawings and specifically claimed.

In the accompanying drawings like characters of reference indicate like parts in the several views, and:

Figure 1 is a plan view of the invention showing the ring holder associated therewith.

Figure 2 is a section on the line 2—2 of Figure 1.

Figure 3 is a greatly enlarged detail section on the line 3—3 of Figure 1 showing one end of the traveler in running position.

Figure 4 is a view similar to Figure 1 but with the traveler dropped from running position.

Figure 5 is a detail section through a modified construction of the ring.

In the embodiment of the invention as here disclosed there is provided, in the preferred form, a ring made from a punched and formed sheet metal, the metal employed being preferably steel. This sheet is punched to form an annulus which is formed to provide an inverted frusto-conical body 10 having a flange 11 depending from its outer edge and having a bead 12 extending in cross-section about three-fourths of a circle formed below the inner edge of the body. This segmento-circular bead extends well below the lower edge of the flange 11. By means of this construction the ring fits in the usual holder which has a flat annular base 13 provided at its inner periphery with an upstanding flange 14 and on its outer periphery with spring clips 15 for holding the ring in proper position with the bead spaced from the flange 14 and on its outer periphery with spring clips 15 for holding the ring in proper position with the bead spaced from the flange 14 and having its top substantially level with the upper edge of said flange. Also the holder has lugs 16 projecting outwardly from the base, these lugs being slotted to receive the usually holding down screws.

The traveler consists of a single length of fine wire, preferably of the grade known as spring steel or piano wire. This wire is bent to provide a body portion 17 the length of which is considerably less than the internal diameter of the ring. A leg 18 depends from each end of this body 17 and terminates in a downwardly and outwardly arcuately curved foot 19 having a radius greater than the radius of the bead 12, the radius of the foot being about twice that of the bead. The body, legs and feet all lie in the same plane and the lateral projections of the feet are such that these distances are much greater than the corresponding distances between the vertical center lines, bead 12 and flange 14 and causing the traveler to hook against the largest diameter of the bead, and thus the traveler is securely held in cooperative relation to the ring and cannot become accidentally disengaged therefrom.

Moreover, the outward and upward curve of the traveler foot 19 causes the traveler to run without coming in contact with the traveler ring holder support 15 whereas the old style of traveler with a straight foot would, if extended past the proper length, quickly cut off the traveler ring holder support 15.

In the modification of the ring shown in Figure 5 there is disclosed a ring turned to shape to provide a frusto conical body 20, internal bead 21 and external flange 22, the ring thus having the same general shape as the sheet metal ring previously described. Thus, either the sheet metal ring or the ring

of Figure 5, which may be termed a solid ring, may be used with the traveler since they are essentially the same so far as their cross sections cooperate with the traveler although the sheet metal ring is simpler and more economical to manufacture.

By an inspection of Figure 3, which shows the traveler in running position, it will be seen that the construction provides for but a single contact point between the foot of the traveler and the bead, the curvatures of these parts being tangential and, because of the circular cross section of the wire, the tangential contact is linked to a one point contact. Furthermore, under no circumstances can the terminal end of the wire contact in running position with any part of the ring since the instant the traveler is raised the bead and curved feet will fit together with the bead in the lowest part of the curved foot. Because of this friction between the traveler and ring is reduced to a minimum and very little lubricant is necessary so that the ring construction is reduced to the simple form of a one piece ring. Moreover, any wear of the ring that may take place due to long continued use will take place along the bottom of the bead and will only have the effect of burnishing the bead along this part so that a highly polished surface will be produced over which the traveler will slide with substantially no frictional resistance.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. The combination of a spinning ring having a depending bead on its inner periphery, a traveler having foot portions adapted to engage beneath the bead and contacting tangentially with said bead, said foot portions being each curved to a radius greater than the bead with the concave side adjacent the bead, and a ring holder provided with an upstanding internal flange concentric with and spaced from the ring a distance less than the lateral extension of each foot portion of the traveler.

2. The combination of a spinning ring having a depending bead on its inner periphery, with a traveler formed of a single length of wire having a body portion provided with a depending leg at each end terminating in a foot curved downwardly and outwardly from the leg to form an arcuate portion having its concave side uppermost and tangentially en-

gaging the bead, and a ring holder provided with an upstanding internal flange concentric with and spaced from the ring a distance less than the lateral extension of each foot portion of the traveler.

5 3. The combination of a spinning ring having a depending bead on its inner periphery, with a traveler formed of a single length of wire having a body portion provided with
10 a depending leg at each end terminating in a foot curved downwardly and outwardly from the leg to form an arcuate portion having its concave side uppermost and tangentially engaging the bead, the radius of curvature of each foot being greater than the radius of the bead, and a ring holder provided with an upstanding internal flange concentric with and spaced from the ring a distance less than the lateral extension of each foot portion
15 of the traveler.

20 In testimony whereof I affix my signature.
WILLARD T. MUNSON.
